UNITED STATES PATENT OFFICE.

PATRICK J. MORAN, OF EAST CLEVELAND, OHIO.

BLAST FURNACE.

Application filed March 17, 1922. Serial No. 544,612.

To all whom it may concern:

Be it known that I, PATRICK J. MORAN, a citizen of the United States, resident of East Cleveland, county of Cuyahoga, and 5 State of Ohio, have invented new and useful Improvements in Blast Furnaces, of which the following is a specification, the principle of the invention being herein explained and the best mode in which I have 10 contemplated applying that principle, so as to distinguish it from other inventions.

This invention relates to blast furnaces, and more particularly to the construction of the throat portion of the blast furnace 15 stack.

It is an object of the invention to lessen the amount of fine ore, limestone and coke which is carried off with the furnace gases through the downcomers.

20 A further object is to lessen the destructive effect of sudden surges of gas caused by slips in the body of ore being treated in the furnace.

A further object is to provide a protective shield for the furnace wall adjacent the 25 charging hopper which can be readily put in place or removed from the furnace. Further objects are to so mount the shield that it is free to expand and contract independently of the furnace wall, to provide a flexible supporting means for the shield to enable it to better withstand the impact of the material delivered from the hopper, and to provide detachable connections for the 30 supporting means on the outside of the furnace so that in case the shield is damaged it can be dropped into the furnace.

The annexed drawings and following description set forth in detail certain means 35 embodying my invention, the disclosed means, however, constituting but one of the various mechanical forms in which the principle of the invention may be employed.

In said annexed drawings:

40 Fig. 1 shows a central vertical section through the upper end of the blast furnace stack taken on the line I—I of Fig. 2.

Fig. 2 shows a horizontal section taken on the line II—II of Fig. 1.

45 Fig. 3 shows a central vertical section through the upper end of the blast furnace stack similar to Fig. 1 and taken on line III—III of Fig. 4 and showing a modified form of the invention in which the shield and suspension rods are water cooled.

Fig. 4 shows a horizontal section taken on line IV—IV of Fig. 3.

Fig. 5 is a detail sectional view showing one of the water cooled suspension rods and 60 one of the connections by means of which water is circulated through the rods and shield.

Fig. 6 is a detail sectional view of a modified form of suspension rod.

Referring to the annexed drawings, the 65 numeral 1 indicates the blast furnace stack which is of the usual conical construction tapering toward the top. The stack 1 is provided at the top thereof with the usual charging hopper 2 controlled by the bell 3. 70 Immediately below the charging hopper the wall of the stack is of reduced thickness to provide a throat portion 4 of enlarged diameter. Downcomer conduits 5 and bleeder conduits 6 of the usual type communicate 75 with the throat portion 4 of the stack.

In the operation of blast furnaces the 80 large volumes of gas constantly leaving the stack at high velocity through the downcomers carry in suspension a considerable quantity of fine particles of ore, limestone and coke which are hard to remove from the gas and necessitates expensive cleaning 85 systems to remove. The enlarged throat portion 4 in applicant's stack provides an expansion chamber where the velocity of the gases is reduced prior to entering the downcomers, whereby the carrying capacity of the gases is lessened and a large portion of the suspended solid matter settles back 90 into the furnace. The enlarged throat portion 4 also serves to lessen the destructive violence of blow outs through the bleeder conduits occasioned by slips in the body of 95 ore being treated.

In order to protect the wall of the stack from the impact of the materials discharged over the bell 3 from the hopper 1 and to deflect the materials to the center of the furnace, I suspend a cylindrical metallic 100 shield 8 below the hopper 2 within the enlarged throat portion 4 of the stack. The cylindrical shield 8 consists of a plurality of sections 9 having outwardly extending abutting flanges 10 detachably secured together by means of bolts 11. Each section 9 of the shield 8 is suspended by means of a pair of rods 12 which pass through slightly enlarged holes 13 formed in the top portion of the stack wall. The rods 12 have 105 110

2

nuts 14 at their upper ends which project through the top of the stack by means of which the rods are suspended. The rods 12 are connected to the upper edge of each shield section 9 adjacent the ends thereof by means of detachably connected links 15. The joints between the sections 9 are so disposed with respect to the bleeder and downcomer passages that the suspension rods 12 are positioned clear of the passages. The enlarged holes 13 permit the rods to have a slight swinging movement which, together with the links 15 provides a flexible suspension for the shield 8 so that the wear due to the impact of material is decreased. The shield being spaced from the wall of the stack is free to expand and contract under the influence of the heat of the furnace.

As shown in Fig. 1 the diameter of the shield 8 is slightly less than the diameter of the stack beneath the enlarged throat portion so that in the event that the shield is so seriously damaged during the operation of the furnace that it is rendered useless the nuts 14 can be removed and the whole shield dropped into the furnace.

In the modification shown in Figs. 3, 4 and 5 the shield 16 consists of a series of sections 17 similar to the sections 9 of the shield 8 except that each section 17 has coils 18 of wrought iron pipe cast therein the ends of which extend to the upper edge of the sections. The shield 16 is detachably suspended from the top of the furnace by means of tubular rods 19 having a pivotal connection with lugs 20 on the upper edges of the sections 17 adjacent the ends thereof and suspended by means of nuts 21 at the top of the furnace. The adjacent coils 18 in each section 17 are connected at their upper ends by detachable fittings 22, and the coils adjacent the ends of each section are connected to the tubular suspension rods by means of detachable elbow fittings 23. Alternate suspension rods are detachably connected at their upper ends respectively, with feed and discharge conduits 24 and 25. By means of the connections above described water can be circulated through the suspension rods 19 and coils 18 in the shield 16. By reason of the detachability of the connections, any one of the shield sections can be detached from the pipes 24 and 25 in case the water circulatory system there-through becomes impaired. In case one of the coils 18 should become damaged connection can be made across the damaged coil and between the coils on opposite sides thereof.

In Fig. 6 is shown a modified form of water cooled tubular suspension rod 26 which is pivotally connected to a lug 27 on a shield 28 and is detachably supported by means of nuts 29 on the top of the furnace. Within the tubular rod 26 is a smaller tube

30, the open lower end of which terminates adjacent the lower closed end of the tube 26. The upper ends of the tubes 26 and 30 communicate by means of detachable fittings 31 and 32 with feed and discharge conduits 24 and 25, respectively.

Having fully described my invention what I claim as my invention and desire to secure by Letters Patent is:

1. The combination with a blast furnace stack provided with a charging hopper at its upper end; of an internal metallic shield cylindrical throughout within said stack adjacent said hopper, said shield conforming to the internal configuration of said wall and spaced therefrom.

2. The combination with a blast furnace stack provided with a charging hopper at its upper end; of a metallic shield cylindrical throughout of less diameter than the internal diameter of said stack; and means for supporting said shield immediately below said hopper.

3. The combination with a blast furnace stack provided with a charging hopper at its upper end; of a cylindrical metallic shield of less diameter than the internal diameter of that part of the stack wall laterally adjacent to said shield, the latter being supported below said hopper; said internal diameter being greater than that of the interior of the stack below said shield, whereby an enlarged annular space surrounding said shield is formed.

4. The combination with a blast furnace stack provided with a charging hopper at its upper end; of an annular metallic shield of less diameter than the internal diameter of said stack; and means for yieldingly and detachably suspending said shield within said stack below said hopper.

5. The combination with a blast furnace stack provided with a bell and hopper at its upper end; of an annular metallic shield composed of detachably connected sections and of less diameter than the internal diameter of said stack; and flexible means detachably connected to the upper end of said stack for supporting said shield within said stack below said hopper.

6. The combination with a blast furnace stack having a charging hopper at its upper end and an enlarged throat portion beneath said hopper; of a concentrically disposed annular metallic shield in said throat portion, said shield being of slightly less diameter than the internal diameter of said stack immediately beneath said throat portion; and suspending means for said shield including connections accessible from outside the stack whereby said shield may be dropped into the furnace.

7. The combination with a blast furnace stack having a bell and hopper at its upper end; of a concentrically disposed annular

metallic shield of greater diameter than said bell but of less diameter than the internal diameter of said stack detachably suspended within said stack beneath said hopper.

5 8. The combination with a blast furnace stack provided with a charging hopper at its upper end; of an annular metallic shield of less diameter than the internal diameter of said stack; and water cooled suspension rods depending from the top of the furnace 10 for supporting said shield immediately below said hopper.

9. The combination with a blast furnace stack provided with a charging hopper at 15 its upper end; of an annular metallic shield of less diameter than the internal diameter of said stack; suspension rods for supporting said shield beneath said hopper, said rods and said shield being provided with 20 passages for a cooling fluid; means for connecting the passages in the rods with the passages in the shield; and means for circulating a cooling fluid therethrough.

10. The combination with a blast furnace 25 stack provided with a charging hopper at its upper end; of an annular metallic shield having tortuous passages for the circulation of water therethrough; means for supporting said shield within said stack immedi-

ately below said hopper; and means for 30 supplying water to said passages.

11. The combination with a blast furnace stack provided with a charging hopper at its upper end; of an annular metallic shield beneath said hopper built up of sections, 35 each section of which is provided with internal tortuous passages for a cooling fluid; tubular suspension rods for each of said sections; connections between the said tubular rods and the passages of each of said 40 sections; and means for circulating a cooling fluid independently through the suspension rods and passages of each of said sections.

12. In a blast furnace, the combination with an enlarged throat portion of the furnace; of a shield cylindrical throughout suspended in said portion and spaced from the walls thereof so as to permit of a reduction of the velocity of the gases at the top of the furnace. 50

13. In a blast furnace, the combination of an enlarged throat portion of the furnace; a hopper above said throat portion; and a shield suspended and entirely located in said enlarged throat portion. 55

Signed by me this 21 day of February, 1922.

PATRICK J. MORAN.
